UNITED STATES PATENT OFFICE.

DELLA A. HOLCOMB, OF YOUNGSTOWN, OHIO.

PEN, PENCIL, STOGIE, AND CIGAR HOLDER.

1,213,644.

Specification of Letters Patent.

Patented Jan. 23, 1917.

Application filed June 19, 1913. Serial No. 774,678.

To all whom it may concern:

Be it known that I, DELLO A. HOLCOMB, a citizen of the United States, residing at Youngstown, in the county of Mahoning 5 and State of Ohio, have invented certain new and useful Improvements in Pen, Pencil, Stogie, and Cigar Holders; and I do hereby declare the following to be a full, clear, and exact description of the invention, such as will enable others skilled in the art to which it appertains to make and use the same.

This invention comprehends improvements in pen and pencil holders and relates 15 more particularly to those which are especially adapted for attachment to a pocket or belt in order that pens and pencils may be easily and conveniently carried.

The primary object of the invention re- 20 sides in the provision of a holder of this type which may be very cheaply manufactured so as to sell at a relatively low price, which will form a convenient and practical device, and which may be used for holding 25 a plurality of articles.

Another and more specific object of the invention is to provide a pen and pencil holder formed of a single strip of spring metal by bending said strip so as to provide 30 a U-shaped body and a clamping portion formed upon one side of the body.

The invention also aims to generally improve devices of this nature to render the same more useful and commercially desir- 35 able.

With these and other objects in view, as will become more apparent as the description proceeds, the invention consists in cer- 40 tain novel features of construction, combi- nation, and arrangement of parts, as will be hereinafter described and claimed.

For a complete understanding of my in- 45 vention, reference is to be had to the following description and accompanying drawings, in which,

Figure 1 is a perspective view of the pen and pencil holder, Fig. 2 is a side elevation of the device, showing a pencil secured therein, Fig. 3 is a transverse section taken 50 on the plane of line 3-3 of Fig. 2, and Fig. 4 is a transverse sectional view showing a modified form of holder.

I form my holder from a single piece of spring metal by bending the same back upon 55 itself to form a somewhat U-shaped body having an outer wall 5 and an inner wall

6. At the juncture of the two walls the strip is curved, as indicated by the numeral 7, and forms a spring portion which tends to normally force the upper edges of the 60 walls toward each other. These walls contact with one another adjacent their upper edges and then diverge, as indicated by the numeral 8 so as to form a sort of mouth which will direct a pen or pencil between 65 the walls 5 and 6. The inner wall 6 is formed with a plurality of corrugations 9 which form inwardly opening grooves or channels into which the pens and pencils fit when they are positioned within the 70 holder. These corrugations extend practically the full length of the wall 6 and also tend to reinforce the same and provide a stronger device.

A clamping wall or portion 10 is formed 75 by bending one extremity of the spring metal clip against the face of the inner wall 6, as clearly shown in the drawings. An open loop 11 is formed at the top of the clamping portion 10 and tends to force the 80 latter normally against the wall 6 and the lower edge of the clamping portion is bent away from said wall, as indicated by the numeral 12, so that a pocket wall, belt, or other support may be easily inserted between the clamping portion and body of the holder.

In Fig. 4 I have shown a modified form of the device, wherein the walls 13 and 14 are both of a corrugated or wavy construc- 90 tion so as to form a plurality of pockets 15, in which various articles, such as pens, pencils, stogies, and cigars, may be held. If desired, the outer wall of the holder may be slit longitudinally for a distance 95 from its upper edge, as indicated by the numeral 16 so that the outer walls of the pockets may spring independently of one another so as to hold articles of different sizes. It is to be understood that I may 100 provide only the outer wall 5 with corrugations if desired.

From the foregoing description taken in connection with the accompanying drawings, it will be apparent that I have provided an extremely simple holder, which may be very cheaply manufactured so as to sell at a relatively low price. This holder will prevent the points of pencils being broken and also prevent cigars, stogies, etc. 110 being crushed.

While I have shown and described the

preferred embodiment of my invention, I do not wish to be limited to this exact construction, combination, and arrangement of parts, but may make such changes as will fall within the spirit and scope of the invention as defined by the appended claim.

Having thus described my invention, I claim:—

A device of the character set forth formed of a single strip of flat metal having its opposite ends looped to provide transversely arranged spring portions, said ends bent to lie back upon the body in opposite directions, one of said ends forming a clamping

member, the opposite end forming an outer 15 wall, the face of the body opposing the inner face of the outer wall provided with a plurality of longitudinally extending corrugations forming pockets and being provided with an outwardly inclined upper end 20 to permit articles to be readily inserted in the pockets.

In testimony whereof I affix my signature in presence of two witnesses.

DELLO A. HOLCOMB.
